CLAIM

I claim the ornamental design for a stackable container with eccentric neck, as shown and described.

DESCRIPTION

FIG. 1 is a perspective view from the front of the stackable container with eccentric neck;

FIG. 2 is a front elevation view of the stackable container with eccentric neck of FIG. 1;

FIG. 3 is a rear elevation view of the stackable container with eccentric neck of FIG. 1;

FIG. 4 is a right-side elevation view of the stackable container with eccentric neck of FIG. 1;

FIG. 5 is a left-side elevation view of the stackable container with eccentric neck of FIG. 1;

FIG. 6 is a top plan view of the stackable container with eccentric neck of FIG. 1; and,

FIG. 7 is a bottom plan view of the stackable container with eccentric neck of FIG. 1.

The portions shown in broken lines are for illustrative purposes only and form no part of the design.

1 Claim, 7 Drawing Sheets
